(57) **CLAIM**

The ornamental design for a clog, as shown and described.

DESCRIPTION

1. Clog

1.1 : Perspective

1.2 : Top

1.3 : Front

1.4 : Bottom

1.5 : Back

1.6 : Right

1.7 : Left

The reproductions of the design show a right clog, the corresponding left clog being the mirror image of the one shown in the reproductions; the clog is characterized in that the sole and upper are formed by a single piece; the clog is made of thermoplastic polymer; the clog surface has a granular appearance; the clog comprises a U-shaped strap, which swivels and is attached to the rear edge of the upper; the clog upper and the strap are openwork, with holes; the clog upper has a raised crater-shaped lower band; the inner side of the sole is raised; the outer side of the sole has ten straight transverse bands which are separated by straight transverse grooves and which are cut by two long longitudinal grooves slightly curved (adapted to the contour of the sole); the shadows appearing on the reproductions are not part of the design whose protection is claimed.
